UNITED STATES PATENT OFFICE

169,394

TEA BAG HOLDER

John Roman, Elizabeth, N. J.

Application December 30, 1952, Serial No. 22,920

Term of patent 3½ years

(Cl. D44—26)

To all whom it may concern:

Be it known that I, John Roman, a citizen of the United States of America, residing at Elizabeth, in the county of Union and State of New Jersey, have invented a new, original, and ornamental Design for a Tea Bag Holder, of which the following is a specification, reference being had to the accompanying drawing, forming part thereof.

In the drawing

Fig. 1 is a front elevational view of a tea bag holder, showing my new design;

Fig. 2 is rear elevational view thereof;

Fig. 3 is a top plan view thereof; and
Fig. 4 is a side elevational view.

I claim:

The ornamental design for a tea bag holder, substantially as shown.

JOHN ROMAN.
